DESIGN FOR A COIN CONTROL DEVICE FOR VENDING MACHINES

Joseph W. Srodulski, Chicago, Ill.

Application February 18, 1938, Serial No. 75,249

Term of patent 7 years

To all whom it may concern:

Be it known that I, Joseph W. Srodulski, a citizen of the United States, and a resident of Chicago, in the county of Cook and State of Illinois, have invented a new, original, and ornamental Design for a Coin Control Device for Vending Machines, of which the following is a specification, reference being had to the accompanying drawing forming a part thereof, and in which:

Fig. 1 is a perspective view of a coin control

device for vending machines, showing my new design;

Fig. 2 is a front elevational view of the same at a slightly reduced scale; and

Fig. 3 is a fragmentary top plan view of the same, likewise at reduced scale, as seen from line 3—3 of Fig. 2.

I claim:

The ornamental design for a coin control device for vending machines, as shown.

JOSEPH W. SRODULSKI.
